UNITED STATES PATENT OFFICE.

ROBERT F. MILFORD, OF LOST CABIN, WYOMING.

BIT OR REAMER TRUCK.

SPECIFICATION forming part of Letters Patent No. 650,981, dated June 5, 1900.

Application filed November 2, 1899. Serial No. 735,627. (No model.)

To all whom it may concern:

Be it known that I, ROBERT F. MILFORD, a citizen of the United States, residing at Lost Cabin, in the county of Fremont and State of Wyoming, have invented a certain new and useful Bit or Reamer Truck, of which the following is a specification, reference being had therein to the accompanying drawings.

This invention relates to improvements in trucks, and has more particular relation to trucks for moving heavy machinery, and especially drilling-bits and augers for wells.

The invention consists of the combination, with a suitable wheeled frame, of a swivel-head mounted on one end of the same.

The invention also consists of certain other novel constructions, which will be hereinafter more particularly set forth and claimed.

In the accompanying drawings, forming part of this specification, Figure 1 represents a perspective view of a truck embodying my invention with the bit in the position it occupies when being secured into its shaft. Fig. 2 represents an enlarged detail central transverse section through the swivel-head. Fig. 3 is a top plan with the bit in position on the truck for moving.

1 1 in the drawings represent the truck-wheels; 2, the frame connecting the same; 3, the truck-frame proper; 4, the swivel-head, and 5 the sliding clamp. Said frame 2 is formed upon its upper surface with a centrally-arranged groove 6 and at the sides thereof smaller grooves 7 7, the latter being 35 for the reception of the rods 8, which form the frame 3, the forward portion of said rods being connected by a pendent loop 9, adapted to form a rest for the truck when not in use. The said rods 8 8 extend parallel to each 40 other, so as to form guides for the sliding clamp 5. This latter comprises a suitable casting, provided at each end with an eye 10, adapted to slide upon its respective rod 8, and at its middle with two vertical spring 45 clamping-arms 11 11, between which the bit or reamer is adapted to be clamped. When so applied in position, said bit or reamer rests within the groove 6, and is thus prevented from moving laterally. The rear ends 50 of the rods 8 8 are bent, respectively, to form eyes 12 12, which receive suitable trun-

nions 13, formed upon diametrically-opposite sides of the head 4, whereby the latter may have a pivotal movement in relation to the said rods. This head 4 is further provided 55 with a swivel-clamp 14, which comprises a vertical shaft 15, journaled in said head, two spring clamping-arms 16 16, arranged upon the upper end of said shaft, and a head or nut 17, formed upon the lower end of said 60 shaft for securing the same upon the head 4. When the bit is applied in position, as above described, its lower end is secured in the spring clamping-arms 16. When the bit is to be applied in position upon its shaft, the 65 truck is first rolled directly under said shaft and the front ends of the rods 8 8 raised to lower the head 4, so that the bit may be passed under its shaft. The said forward end of the frame 3 is then lowered to force the head 4 70 upward and cause the upper screw-threaded end of the bit, which has previously been disengaged from the clamp 5 and grooves 6 and raised to a vertical position, to engage the screw-threads of the shaft. Said bit may 75 then be rotated to secure it firmly in position upon its shaft, because of the swivel-mounting of the clamp 14, upon which it is resting. By this means augers or bits of great weight 80 may be conveniently handled and moved from place to place as the drilling proceeds and applied or detached from their respective shafts at will. It will further be observed that by the peculiar trunnion connection between the head 4 and the truck-frame I am 85 enabled to tip the truck to any inclination without affecting the position of the article resting upon said head. The sliding clamp-frame 5 may be readily adjusted along the rods 3 to receive the ends of any-sized drills 90 or reamers. I also contemplate raising the bit into operative position by attaching a suitable tackle to the frame of the truck, so as to raise it into a vertical position, with the head resting upon the ground, so that the 95 swivel-clamp may be rotated to screw the bit into position. By this mode of operation the bit is not removed from the sliding clamp 5 and the groove 6, but the whole truck-frame is tipped to bring the frame into the proper 100 vertical position.

I do not care to limit my invention to drill-

ing bits or reamers, as the same may be aptly employed for the transportation and application of any form of machinery.

Having thus described my invention, what I claim as new, and desire to secure by Letters Patent, is—

1. The combination with a wheeled frame, a spring-clamp mounted on one end of the same, and a swivel-clamp mounted upon the opposite end, substantially as described.

2. The combination with a wheeled frame, of a head pivotally mounted upon one end, a spring-clamp having swivel connection with said head, and a spring-clamp adjustably mounted upon the opposite end of said frame, substantially as described.

3. The combination with two wheels, a frame connecting the same and formed with a transverse groove, parallel rods applied to said frame and formed into eyes at their rear ends, a head having trunnions mounted in said eyes, a spring-swiveled clamp mounted on said head, and a sliding spring-clamp mounted on the opposite ends of said parallel rods, substantially as described.

In testimony whereof I affix my signature in presence of two witnesses.

ROBERT F. MILFORD.
